BATTERY LIFTER

John W. Speaker, Milwaukee, Wis.

Application September 13, 1946, Serial No. 696,894

3 Claims. (Cl. 294—92)

1

This invention relates to storage battery lifters and refers particularly to the strap type of lifter wherein a flexible insulating strap has clips on the ends thereof to grip the terminal posts of the battery.

It is an object of this invention to improve battery lifters of this general type to the extent of minimizing the strain imposed upon the battery terminals.

Another object of this invention is to simplify the construction of such battery lifters and to obviate the need for rivets or other similar fastenings in the attachment of the clips to the strap.

One of the most serious disadvantages of battery lifters heretofore available resides in the fact that the clips would often slip off the posts, especially where the posts have become worn and as a result are undersize. It is therefore a further object of this invention to provide a battery lifter having clips provided with complementary jaws which approach each other in consequence to the application of lifting force and in which the minimum distance between the jaws is less than the diameter of the smallest battery post that might be encountered.

With the above and other objects in view, which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates one complete example of the physical embodiment of the invention constructed according to the best mode so far devised for the practical application of the principles thereof, and in which:

Figure 1 is a perspective view illustrating the battery lifter of this invention applied to a storage battery preparatory to the application of lifting force thereon;

Figure 2 is a perspective view illustrating the top side of one of the clips;

Figure 3 is a perspective view illustrating the back side of the clip;

Figure 4 is a longitudinal sectional view through one of the clips and illustrating the relative positions of the parts upon initial application of the clip to a battery terminal post; and

Figure 5 is a view similar to Figure 4 but showing the parts in their respective positions during the application of lifting force on the clip.

2

Referring now particularly to the accompanying drawing, the numeral 6 designates a flexible strap of any suitable insulating material, the ends of which have clips generally designated by the numeral 7 attached thereto and by which the carrying strap may be connected to the terminal posts 8 and 9 of a storage battery 10.

Each clip 7 comprises a main member 11 stamped from flat sheet steel or the like and having angularly disposed legs 12 and 13. The leg 13 has a transverse slot 14 in its end portion which is bent out slightly as shown, and is pierced with a U-shaped cut 15 at a point adjacent to the juncture or corner defined by the angularly disposed legs 12 and 13. The end of the strap 6 is woven through the slot 14 and the opening defined by the cut 15, which in a sense provides a second transverse slot. The metal lying within the U-shaped cut 15 forms a tongue 16 which presses the end portion of the strap 6 against the transverse edge of the cut 15. The metal of which the stamping is made is stiff enough so that the tongue 16 upon being pressed down against the strap secures the same in position and thus entirely obviates the need for rivets or other fastening means in the attachment of the strap to the clip.

The leg 12 of the stamping has a round hole 17 of a size to loosely receive any terminal post of a storage battery. The edge portion of the hole which is farthest removed from the juncture or corner between the legs 12 and 13 serves as a jaw adapted to engage and bite into the post of the battery at one side thereof. The jaw thus provided is, of course, fixed with respect to the strap. A complementary movable jaw is provided by the free edge 18 of a latch plate 19 hingedly connected as at 20 to the main stamping. Preferably, though not necessarily, the free edge of the latch plate has an arcuate notch to increase the extent of its contact with the post.

The hinged connection 20 between the latch plate and the main stamping is conveniently provided by a tongue 21 extended from the inner edge of the latch plate and projecting through an aperture 22 in the main stamping located at the juncture between the leg 12 and the tongue 16. The tongue 21 has its end bifurcated and spread apart after assembly to hold the parts connected.

The relative dimensions of the latch plate 19 and the leg 12 of the main stamping are such that, when the latch plate lies flat upon the leg 12, its free edge portion 18 extends a substantial distance beyond the adjacent edge of the hole 17. Thus, when the latch plate is in this position, the spacing between the complementary

jaws defined by the far edge of the hole 17 and the edge 18 of the latch plate is at a minimum, and considerably less than the diameter of the hole. As the latch plate is swung away from the leg 12, this spacing increases.

Comparison to Figures 4 and 5 illustrates the manner in which reduction in the angle between the latch plate and the leg 12 of the main stamping decreases the spacing between the complementary jaws, this spacing being designated in Figure 4 as x and in Figure 5 as x' . Thus, it will be readily apparent that the provision of the latch plate 19 and the manner in which it is mounted enables the clip to accommodate battery terminal posts of different diameters so that reductions in size of the post resulting from wear will not interfere with the security of the grip by which the clips attach themselves to the posts.

Comparison of Figures 4 and 5 will also show that the application of lifting force to the strap causes the clip to fulcrum about the engagement of the latch plate with the post, thereby reducing the angle between the latch plate and the leg 12 and effecting a shortening of the space x between the complementary jaws.

Another advantage of the present construction lies in the fact that the main stampings can all be identical as the difference in diameter between the positive and negative terminal posts of storage batteries is accommodated by the latch plates. It may be desirable to provide latch plates of two different sizes so that the edge 18 of one of which approaches the far edge of the hole 17 more closely than the other. The two sizes of latch plates may be conveniently stamped from differently colored stock, or one may be plated and the other not, so that in assembling the clips to the strap one of each can be quickly and easily identified.

From the foregoing description, taken in connection with the accompanying drawing, it will be apparent that this invention provides a substantial improvement in battery lifters, particularly by reason of the fact that worn and undersized terminal posts are gripped as securely as properly sized posts, and further, by virtue of the fact that as the strap is bowed outwardly, as shown in Figure 1, when its clips are applied to the battery posts, the lifting force is more nearly straight up and down, thus minimizing the lateral strain on the posts.

What I claim as my invention is:

1. In a storage battery lifter: a flexible strap; a stamping having angularly disposed legs, one of which has a hole therethrough of a size to loosely receive the terminal post of a battery, the other leg of the stamping having spaced trans-

verse slots through which the end portion of the carrying strap is threaded; a tongue on said stamping opposite one edge of one of said transverse slots pressing the strap against said edge of the slot; said stamping having an aperture at the juncture of its angularly disposed legs; a stamped latch plate; a tongue on said latch plate received in the aperture at the juncture of the angularly disposed legs hingedly connecting the latch plate to the stamping with the latch plate lying between the angularly disposed legs so that the free edge of the latch plate serves as a movable jaw to co-act with the far edge of the hole to grasp a battery terminal post therebetween, the distance between said edges decreasing with a reduction in the angle between the latch plate and the leg of the main stamping having the hole therein.

2. In a storage battery lifter of the type comprising a flexible insulating strap and a clip at each end of the strap adapted to grip a terminal post of a battery, means for securing each clip to the strap comprising: a substantially flat leg extending from the clip, said leg having a transverse slot therethrough near its end remote from the clip and a U-shaped cut intermediate said slot and the clip, with the legs of the U facing away from said slot, the tongue defined by said cut being bent out of the plane of the leg and adapted to cooperate with the body of the leg to confine a strap woven through said slot and through the space between the body of the leg and said tongue.

3. In a battery lifter of the type comprising a flexible insulative strap and a clip at each end of the strap adapted to grip a battery terminal post, means for securing each clip to the strap comprising: a substantially flat leg extending from the clip, and having a pair of spaced openings therethrough through which the strap is adapted to be woven; and a cooperating tongue struck from the body of the leg adjacent one of the openings adapted to pinch the strap against the portion of the leg between the openings.
